UNITED STATES PATENT OFFICE.

EUGENE M. ANDERSON, OF WASHINGTON, IOWA.

GRAIN-BOARD FOR WAGONS.

No. 880,493.

Specification of Letters Patent.

Patented March 3, 1908.

Application filed September 4, 1907. Serial No. 391,402.

To all whom it may concern:

Be it known that I, EUGENE M. ANDERSON, a citizen of the United States, residing at Washington, in the county of Washington and State of Iowa, have invented certain new and useful Improvements in Grain-Boards for Wagons, of which the following is a specification, reference being had therein to the accompanying drawing.

10 This invention relates to an improvement in grain-boards for wagons or vehicles, and has for its object the improvement of the construction of a detachable throw-board, which can be quickly secured in position upon the 15 body of a wagon.

Another object of the invention is the improvement of the construction of a throw-board for directing grain into the body of a vehicle, and which throw-board constitutes a 20 section of the body whereby, by adding a plurality of sections upon the body *per se*, the same may be increased in height for accommodating material or stock conveyed in the body.

25 With these and other objects in view, the invention consists of certain novel constructions, combinations, and arrangements of parts, as will be hereinafter fully described and claimed.

30 In the drawings: Figure 1 is a perspective view of a device constructed in accordance with the present invention, and showing said device mounted upon a wagon body. Fig. 2 is a transverse, sectional view of the structure depicted in Fig. 1, and Fig. 3 is a similar view showing a reinforcing member attached to the device and the wagon body. Fig. 4 is a fragmentary sectional view of the grain-board or throw-board device. Fig. 5 is a 35 fragmentary, sectional view of another embodiment of the present invention.

Referring to the drawings by numerals, 1 designates, preferably, a wagon body, upon one side of which is detachably mounted a 45 device constructed in accordance with the present invention.

50 My grain-board device comprises primary, vertical supporting members 2 and auxiliary supporting members 3. The auxiliary members are positioned within the body, while the primary members or bars are positioned outside of the body. The members are so assembled as to place the same in pairs, each

pair consisting of a primary member or bar 2 and an auxiliary member or bar 3. Each 55 pair of members is secured together by preferably, a plurality of bolts 4, which are provided with ordinary nuts 5. The bolts 4 are placed near the upper end of the auxiliary members, and intermediate the ends of the 60 primary members, the bolts 4 being positioned above the upper edge of the side of the body, so that the device can be quickly positioned upon the body, thereby placing the primary member upon the outer face of the 65 side and the auxiliary members upon the inner face of the same side. It will be noted that by reason of the employment of a plurality of bolts, independent, pivotal movement of the primary or auxiliary members or 70 bars of each pair is prevented, besides very secure fastening means is provided for retaining the bars of each pair together.

The throw-board comprises a frame 6, which is, preferably, rectangular in shape, 75 and the frame is formed, preferably, from tubular or rod-like material; it will be obvious that other material may be used in constructing the rectangular frame. I, preferably, place upon the frame 6 a wire mesh 7, 80 and if it is desired, any suitable fastening means, as for instance, ordinary staples, may be employed for securing the wire mesh 7 to the primary supporting bars 2. However, the frame is detachably secured to the supporting bars 2 and 3, by means of the bolts 4 and detachable clamps hereinafter described. The lower portion of the frame is positioned between the supporting members of each 85 pair, and the upper horizontal portion of the frame is secured to the supporting bars or members 2 near their upper end, by means of clamps 8. Each clamp comprises a curved body portion 9, a primary shank 10, and an auxiliary shank or portion 11. The primary 95 threaded shank 10 extends through the supporting bar or member 2, and upon its extended end, there is a nut or locking member 12. The frame 6 is positioned within the curved body portion 9 between portions 10 and 11, see Fig. 4. By threading the nut 12 upon the primary portion or shank 10, the clamp 8 is clamped or held snugly against the supporting member 2, and the end of portion 11 is partly embedded, as at 13, in 100 the supporting bar or member 2. In Fig. 5,

I have shown a substantially **U** - shaped clamp 14, which is provided with two threaded ends 15, and upon each of these ends, there is threaded a nut or locking member 12. It will be obvious that I may use either type of clamps, Figs. 4 and 5, and by employing said clamps, the throw-board is detachably secured to the supporting member, which supporting members constitute the means for detachably securing the device to the wagon body.

By employing four devices, as above described, the height of the body may be greatly increased, so that the same may be employed as a stock-rack or for hauling material such as hay, straw, and the like. It will, therefore, be seen that my throw-board or grain-board device constitutes a section of a stock wagon, if it is desired to use the same as such.

To strengthen the upper portion of the device, a flexible member, as for instance, chain 16 may be employed; the chain 16 is, preferably, secured, at 17, to the opposite side of the wagon body to that carrying the device, and the upper end of the chain is secured by any suitable fastening means to the upper portion of the device, or it may be secured directly to the frame 6. This chain or flexible member 16 constitutes a brace, although the same is not absolutely necessary, as the long supporting bars or braces 2 constitute a brace for the throw-board, and it will be seen that they are positioned outside of the body and behind the frame 6 and the wire mesh 7. It will also be noted that the auxiliary or short bars or supporting members 3 are not of sufficient height to extend across the throw-board, and, therefore, corn, or any other article, thrown against the wire mesh 7, is not likely to strike against said auxiliary or short bars or braces 3, which in the case of corn on the ear would cause the corn to shell off and result in considerable waste. By reason of the wire-mesh structure of the throw-board, the same offers very little resistance against the wind, besides the same constitutes a cushion or yieldable surface against which the grain or corn comes in contact, as the same is deposited in the wagon body.

When it is desired to transport the device, this may be accomplished by quickly lifting the same off of the body, removing the bolts 4 and the clamps, whereby the primary and auxiliary members or bars 2 and 3, respectively, can be separated and placed in a suitable pile and the throw-board or frame can be laid in a horizontal position or stored as desired.

What I claim is:

1. In a device of the character described, the combination of a pair of supporting members, a frame in engagement with one of said

members, wire mesh carried by said frame, a detachable clamp surrounding a portion of said frame and extending through one of said supporting members, and means securing said clamp upon said supporting member.

2. In a device of the character described, the combination with a supporting member, of a throw-board in engagement with said supporting member, said throw-board comprising a frame, a wire mesh positioned upon said frame, and clamping means extending through said supporting member and surrounding a portion of the frame of the throw-board and securing said throw-board to said supporting member.

3. In a device of the character described, the combination of a pair of supporting members, a throw-board, means detachably securing the lower portion of said throw-board between said members, and clamping means detachably securing the upper portion of said throw-board to one of said supporting members.

4. In a device of the character described, the combination with a wagon body, of a pair of supporting members positioned upon the body, one of said members extending only a short distance above the upper edge of the side and the other member extending a considerable distance beyond the upper edge of the same side, a throw-board in engagement, at its upper portion, with one of said members and its lower portion positioned between said members, a substantially **U**-shaped clamp secured near the upper end of one of said members and only engaging a portion of the upper part of said throw-board, and means securing the lower part of said throw-board to both of the members.

5. In a device of the character described, the combination of a primary and an auxiliary supporting member, the auxiliary member of less length than the primary member, a throw-board positioned contiguous to said primary and auxiliary member, the primary member extending entirely across the throw-board, a detachable clamp extending transversely of said throw-board and primary member and securing the throw-board at its upper edge only to the primary member, and means securing the lower part of said throw-board to the primary and auxiliary members.

6. In a device of the character described, the combination with a vehicle body provided with a vertical side, a throw-board positioned contiguous to said body and directly above said side, of a primary supporting member in engagement with said side and throw-board and extending across and above said throw board, an auxiliary supporting member in engagement with said

side and extending a short distance above the upper edge of the same, detachable fastening means securing the upper portion of said throw-board only to the primary member near its upper end, and means securing the lower portion of said throw-board to said primary and auxiliary members.

In testimony whereof I hereunto affix my signature in presence of two witnesses.

EUGENE M. ANDERSON.
